UNITED STATES PATENT OFFICE.

BERNHARD JACOB, OF SELMA, ALABAMA.

SHUTTER-FASTENER.

SPECIFICATION forming part of Letters Patent No. 309,059, dated December 9, 1884.

Application filed July 17, 1884. (No model.)

To all whom it may concern.

Be it known that I, BERNHARD JACOB, a citizen of the United States, residing at Selma, in the county of Dallas and State of Alabama, have invented a new and useful Improvement 5 in Blind-Fasteners, of which the following is a specification.

In the accompanying drawings, illustrating my invention, Figure 1 is an inside view in 10 elevation of a pair of window-blinds with my improved blind-fastener attached in position thereto. Fig. 2 is a horizontal section in the line $x-x$ of Fig. 1. Fig. 3 is a view of the same, partly in plan and partly in section. 15 Fig. 4 is a detail bottom view of the tube which incloses the actuating-spring and in part the bolt of my improved blind-fastener; and Fig. 5 is a broken sectional view in the line $y-y$ of Fig. 2, looking in the direction of 20 the arrow in the latter figure.

In the figures, A indicates a tube, open at one end and closed at the other, in which is placed a coil-spring, a, with one end abutting against and fastened to the closed end of said tube, while its opposite end is fastened to a pintle, b⁵, attached to the inner end of a bolt, B, which is made to move to and fro within the tube in the act of locking and unlocking the blind-fastener. The tube A, at its top and 25 about midway of its length, is perforated, so as to form a pintle-way, within which the pintle b may travel in the act of locking and unlocking the bolt B, said pintle-way being from its initial point f, on top of the tube, spirally 30 curved, as at b', in a downwardly and forward direction toward the open end b² of the tube, and until it reaches the straight pintle portion b³ at the bottom of the tube A, and which extends forward in a direct line toward the 35 open end b² of the tube, as shown. This pintle-way, partly spiral in form and partly straight, as shown, governs the line of travel of the pintle b, as well as limits the bolt to its full forward and rearward "throw," the pintle b traveling in said "way" during such act. 40

The tube A, as clearly shown in Fig. 1, is firmly fixed to a foundation-plate, g, which is secured to one blind, C, while the bolt-clasp B' is fastened to the fellow blind C'. The bolt 45 B has a lever-plate, as D. This plate has a finger hole or aperture, e, through it, as shown, and its lower inner portion terminates in a

catch, as at i, which, when the blind-lock is in a locked condition, as represented in Figs. 1, 2, and 5, becomes seated in a catch or channel way, i', (see Fig. 3,) of a lock-plate, J, which is secured to the window-sill J' of the window to which the blinds C C' are applied. 5

In operating the blind-lock the operator places his finger in the aperture e of the lever-plate D, then presses laterally in the direction of the arrow, Fig. 2, thus forcing the bolt free from its clasp B', and also compressing the spring a, and moving the bolt laterally to the extent of the straight portion b³ of the 60 pintle-way, in which the pintle b is by such pressure made to travel, and until the plate D has reached the position shown by dotted lines h in Fig. 1. The operator now turns up vertically the lever-plate D and resumes 65 the lateral pressure upon the bolt in the direction of the arrow. This act causes the bolt B to travel farther in a rearward direction, (indicated by the arrow,) the pintle b during such act being made to travel in the 70 curved pintle-way b' until it has reached its seat b⁴ at the top of the tube A, which seat is so formed, as shown, in order to automatically hold the pintle b therein when it is once in 75 position, as represented in Fig. 3. In other words, having reference solely to Fig. 1, the operator presses upon D, thus shoving it to the left-hand, out of lock with the lock-plate J, and until it has reached the dotted lines h. The lever-plate D is now turned up vertically 80 and pressed upon laterally until it has reached the dotted lines h', which act further compresses the spring a, the pintle b meantime traveling in the spiral pintle-way b' until it reaches its seat b⁴. I would here state 85 that the spring a need not be fastened permanently to the pintle b⁵ of the bolt B, and when not so fastened the spring will simply be longitudinally compressed, and yet the same movement of the bolt B in the act of locking 90 be attained.

Having fully unlocked the bolt, as indicated in Fig. 3, the operator, by drawing down upon the lever-plate D, will force the pintle b from its seat b⁴, whereupon the spring a, being released from compression, will instantly force the bolt outwardly from the tube A, and (the blinds being closed, as shown) at the same time throw down the lever-plate D and cause 95 100

its catch *i* to enter the catchway *i'*, as clearly shown in Fig. 5, and thus securely lock the blinds *C* together, as represented in Figs. 1, 2, and 3, against all ordinary intrusion or outside effort to unlock the same.

The above-described fastener I have shown applied to window-blinds; but the same may also be applied to doors or window-sash.

What I claim as my invention, and desire to secure by Letters Patent, is—

The combination of the laterally-sliding and circularly-turning bolt provided with a pintle,

b, and a lever-plate, *D*, with a lock-plate, *J*, and the grooved tube *A*, provided with a spring, *a*, substantially as and for the purpose 15 described.

Witness my hand in matter of my application for a patent for improvement in blind, door, and sash fasteners in presence of witnesses.

BERNHARD JACOB.
